FAUCET FIXTURE OR SIMILAR ARTICLE

Julius Hurwitz, 96-10 57th Ave.,
Forest Hills, N.Y. 11375

Filed Sept. 27, 1965, Ser. No. 87,179

Term of patent 3½ years

(Cl. D91—3)

I claim:

The ornamental design for a faucet fixture or similar article, as shown.
